UNITED STATES PATENT OFFICE.

WILLIAM L. PATTISON, OF ROSEDALE, KANSAS.

DESIGN FOR A GRATING.

Application filed March 5, 1921. Serial No. 450,095. Term of patent 14 years.

To all whom it may concern:

Be it known that I, WILLIAM L. PATTISON, a citizen of the United States, residing at Rosedale, in the county of Wyandotte and State of Kansas, have invented a new, original, and ornamental Design for Gratings, of which the following is a specification, reference being had to the accompanying drawing, forming part thereof.

Fig. 1 is a perspective view of my new design for an ornamental grating, Fig. 2 is a plan view of the same.

What I claim is:

The ornamental design for a grating, as shown.

WILLIAM L. PATTISON.
